OPERATING MEANS.

Application filed December 20, 1924. Serial No. 757,174.

This invention relates to operating means for imparting a back and forth movement to decks, screens and other operating frames mounted for vibratory movement, and more particularly to means for producing a progressive movement.

Various constructions have been proposed heretofore for producing a progressive vibratory movement, but difficulty has been experienced in developing a strong, durable mechanism that is simple in construction and which will produce the desired movement.

An important feature of the present invention, therefore, resides in a simple and satisfactory form of operating means for imparting a progressive movement to decks, screens and other frames mounted for vibratory movement.

Operating means of the type to which the present invention relates are extensively used to operate decks, screens and other machines that produce considerable dust. It is therefore important that the construction of the operating parts be such that they will not be injured by this dust. Another feature of the invention therefore resides in the construction by which dirt and dust are excluded from the bearings of the operating means.

Other features of the invention and novel combination of parts in addition to the above will be hereinafter described in connection with the accompanying drawings which illustrate good practical forms of the invention.

In the drawings:—

Fig. 1 is a side elevation of a frame mounted for back and forth movement and provided with the operating means of the present invention.

Fig. 2 is a view similar to Fig. 1, but shows a modified form of operating means.

Fig. 3 is a view similar to Fig. 1, but shows still another form of operating means.

Fig. 4 is a plan view of Fig. 1, with the upper frame removed from its supporting carriage.

Fig. 5 on an enlarged scale is a view partly in side elevation and partly in section of the operating shaft and associated parts; and

Fig. 6 is a side elevation of another modified form of operating means, the operating shaft being shown in section.

The operating mechanism of the present

invention may be employed for various purposes and is shown in position to operate a frame 10 which may constitute a concentrator deck, a screen frame which supports the ordinary screen clothing or other device.

The frame 10 is mounted upon the carriage 11, which is supported for back and forth movement in the direction of its length by a supporting base of any suitable construction. This base may consist of longitudinally extending beams 12 secured to uprights 13, and the uprights may be connected by laterally extending braces 14.

Various means may be employed for supporting the carriage 11 for back and forth movement, and in the construction shown this is accomplished by transversely extending shafts 15 disposed near the opposite ends of the supporting base. Each shaft 15 is rotatably mounted in a bracket 16 mounted upon the supporting base. The opposite ends of each shaft 15 are provided with downwardly extending arms 17, near the lower ends of which are provided laterally extending stub shafts 18 that are journaled in bearing brackets 19 rigidly secured to the under face of the carriage 11. The arrangement is such that as the arms 17 rock back and forth about the axis of the shaft 15 a slight rising and falling movement is imparted to the carriage 11 and frame mounted thereupon.

The operating mechanism of the present invention is constructed to impart a progressive movement to the frame 10 and in the construction shown the progressive movement will be in a right-hand direction, as indicated by the arrow, so that the materials being treated will move under the action of the operating means lengthwise of the frame 10 towards the right-hand end of the same.

Yielding means is employed for urging the carriage 11 and frame 10 in a right-hand direction, consisting of one or more coiled springs 20, one end of which may rest in a cup that is secured to a block or bracket 21 fastened to the under face of the carriage 11, and the opposite end of each spring rests in a cup 22 secured to and adjustably supported by a threaded shaft 23 having threaded engagement with a bracket 24 that is rigidly secured to an upper portion of the supporting base. The tension of the springs 20 may be varied as desired by turning the hand wheel 25 upon each threaded shaft in

one direction or the other, and each shaft may be secured in the desired position of adjustment by tightening the nuts 26.

One or more cables may be employed for moving the carriage 11 and frame mounted thereupon in a left-hand direction against the tension of the springs 20, and the eccentrics that actuate the cables may be disposed in various positions relative to the cables to 10 tension and slack off the cables.

In Fig. 1 two operating cables 27 are shown. One end of each of these cables is secured to a block or bracket 28 fastened to the under face of the carriage 11 and the opposite end 15 of each cable is adjustably anchored to the supporting base by a threaded bolt 29. The length of these cables may be adjusted by 20 adjustable nuts 30 on the bolt 29. Back and forth movement is imparted to the frame 10 in the present case by exerting a laterally displacing pressure upon an intermediate portion of each cable 27 to pull the frame 10 in a left-hand direction, and then the cables are slackened off to permit the frame 10 to 25 move in a right-hand direction under the action of the springs 20. This is accomplished in the construction shown in Fig. 1 by providing a transversely extending operating shaft 31, the ends of which are journaled in 30 bearing brackets 32 supported by the machine base, and this shaft 31 is provided with a relatively long eccentric portion 33 upon which are mounted the sheaves 34, each 35 of which is provided with a cable receiving groove. The shaft 31 may be driven by a pulley 35. The sheaves 34 are not mounted directly upon the eccentric 33, but anti-friction bearings 36 are provided between the eccentric and the central bore of the hub 40 portion 37 of each sheave so that the eccentric may rotate within the sheaves without 45 rotating the latter. This construction serves to move the sheaves bodily in an orbital path to force each sheave against an intermediate portion of a cable 27 to tension the latter and then move it away from the cable to 50 permit the frame 10 to move in a right-hand direction.

As stated, operating mechanism of the type to which the present invention relates is often used upon decks, screens and other means which produce a large amount of dirt and dust, and in order to prevent this dust from reaching the anti-friction bearings 36, in the construction shown, collars 38 are provided which surround the eccentric portion 33 and are rigidly secured thereto by set screws 39. Each of these collars is provided with an enlarged annular flange portion 40 which fits within the bore of the hub portion 37 of each sheave to close each end of this bore to exclude dirt and dust from the same. The anti-friction means 36 may be variously constructed and, as shown, two 60 anti-friction units 36 of well known con-

struction are mounted upon the eccentric within each sheave. These units are held in spaced relation by a ring 41 which fits the eccentric and each sheave is provided with an annular inwardly extending rib 42 that 70 extends inwardly between the pair of anti-friction units. The arrangement is such that the anti-friction units are held against movement lengthwise of the shaft by the collars 38, and the rib 42 which extends inwardly between the anti-friction units prevents the sheave from moving lengthwise of the shaft. In this manner each sheave 34 is held against movement lengthwise of the driving shaft while at the same time the eccentrics rotate freely within the sheaves to move the latter thru an orbital path, without turning the sheaves. Novel means is provided for supplying a lubricant to the anti-friction bearings. To this end an oil 80 cup 43 is secured to one of the collars so that the lubricant may pass inwardly thru the bore 44 to a groove 45 extending lengthwise of the eccentric portion of the shaft to supply the lubricant to the ring 41. As the 85 shaft rotates the centrifugal force will throw the lubricant outwardly so that it will find its way to each of the anti-friction units 36. The excess amount of lubricant supplied to the bearing will tend to work outwardly between the annular flange 40 of each collar, and the inner bore of the hub 37. This will prevent dirt and dust from entering at this point and thereby excludes the same from the bearings. An annular groove 46 formed 95 in each of the flanges 40 provides a pocket in which the lubricant may accumulate.

From the foregoing it will be seen that as the shaft 31 rotates the eccentric portion 33 of this shaft serves to move each sheave 105 to and from the cable tightening position, and it will be noted that the movement of the sheaves which tightens and slacks off the cables is primarily their movement along the horizontal line A—B, while the 110 tension of the cable is affected only slightly by the movement of the sheaves in the vertical direction. The operating eccentric 33 may be regarded as having a "dead centre" 115 at each end of its stroke where it uses up a period of time during which it neither pulls nor releases the cable appreciably. This occurs when the eccentric is substantially on the line A—B, with the eccentric extending towards A or towards B. When the eccentric extends towards A, the frame 10 is at the left-hand end of its stroke, and when the eccentric extends towards B, the frame 120 10 is at the right-hand end of its stroke.

As the eccentric turns from B to A in a 125 clockwise direction, it stretches the cable taut and pulls the frame in a left-hand direction against the tension of the springs, and as the eccentric passes the dead centre position at A, the slowest movement is imparted to the 130

frame and the direction of movement of the frame is changed, without shifting the materials along the frame. As the eccentric continues its movement in a clockwise direction from A towards B, the cable is slackened off and the springs push the carriage 11 and frame thereupon in a right-hand direction to take up the slack of the cable. When the eccentric reaches the line A—B, the slack is nearly all taken up, but there still remains the final tightening up of the slackened cable, which requires a very short period of time, but this is sufficient to permit the eccentric to pass slightly below the line A—B and cause the sheave to grip the cable suddenly and begin the next backward pull. This quick gripping of the cable, with its backward pull is the important effect, as it arrests suddenly the movement imparted to the frame by the springs 20 and causes the momentum imparted to the materials to slide them along the frame.

The rotation of the eccentric in a clockwise direction from A towards B may be accelerated somewhat by the pull of the cable which promotes a quickened forward stroke, and the pull of the cable against the eccentric as it rotates from B towards A may slow down somewhat the movement of the frame in the left-hand direction and help slow down the turn made by the frame at the left-hand end of its stroke.

The quick grip of the cable above described, as the eccentric passes the point B in rotating downwardly from the line A—B is the important effect in producing the desired progressive movement, but the other result caused by a slight speeding up of the sheave as it moves in one direction and a slight slowing down of the sheave as it rotates in the opposite direction help produce the desired result. The combination of these two influences gives an accelerated forward movement in a right-hand direction with a quick turn at the forward end of the stroke, and a slow backward movement in a left-hand direction with a slow turn at this end of the stroke, with the result that an extremely satisfactory progressive movement is imparted to the frame 10.

If it is desired to arrest the movement of the frame 10 in a right-hand direction more suddenly than can be accomplished by the mechanism described, this may be accomplished by providing a bumper 47 which may be rigidly secured to the supporting base and extends upwardly into position to be struck by the bracket 28, or other part carried by the carriage 11, to stop the movement of the frame.

In the construction shown, the swinging arms 17 which support the carriage 11 for movement in the direction of its length serve also to impart an upthrow movement to the carriage, and this swinging movement may be

utilized to help reverse the movement of the frame 10 at each end of its stroke.

In Fig. 2 of the drawing, a modified form of operating means is shown, in which each cable 48 passes around an idle sheave 49 rotatably supported by the shaft 50, and in order to tension these cables and slack off the same, an eccentric shaft 51, similar in construction and operation to the eccentric shaft 31 above mentioned, is provided with grooved sheaves 52 which act laterally against the portion of the cables which extends from the idle sheave 49 to the anchoring means 53. The operation of the construction shown in this figure is substantially the same as that in Fig. 1, except that since the cables 48 pass around only a small portion of the sheaves 52, the movement imparted to the frame 10 by the mechanism of Fig. 2 will not be as great as that in Fig. 1.

In Fig. 3, still a different modification is shown, in which the cable 54 has one end anchored to the supporting base at 55, and the opposite end is secured at 56 to the upper portion of the levers 57, the lower end of which is pivotally secured to the supporting base at 58. The cable 54 passes around an idle sheave 59 rotatably supported by the shaft 59^a and an intermediate portion of the cable 54 passes part way around the sheave 60 which is mounted upon and actuated by eccentrics upon the eccentric shaft 61. The downwardly extending portion of the cable 54 passes around an idle roller 62 to the anchoring means 55. The upper end of the rocking lever 57 is secured to the frame 10 by the adjustable connection 63. The construction shown in Fig. 3 is a particularly desirable form of operating means when the frame which moves back and forth is supported by rocking arms 17, since the angle thru which these arms swing as the frame moves back and forth under the operating means may be varied as desired by adjusting the position of the clamping nuts upon the bolts 56, 64 and 65. Should it be desirable to employ a stop upon the construction shown in Fig. 3, this may take the form of a bracket 66 rigidly secured to the supporting base and having a portion 67 against which the rocking lever 57 may strike, suddenly to arrest the movement of the frame 10 in a right-hand direction.

In Fig. 6 another modified form of operating means is shown, consisting of an operating lever 68, the lower end of which is pivotally secured to the supporting base at 69, and rocking movement is imparted to this lever by an eccentric shaft 70 which may be provided with an eccentric portion 71 similar to that above described. This shaft, however, instead of being provided with sheaves 34, has a sleeve 72 which surrounds the eccentric and is supported thereupon by anti-friction bearings that may be

similar to the anti-friction bearings 36 above described. The sleeve 72 does not rotate with the eccentric, but is moved thereby thru an orbital path to rock the lever 68 in a right-hand direction, and the lever is shown as having a curved portion which extends part way around the sleeve 72. Rocking movement of the lever 68 may be imparted to the frame 10 by the cable 73, one end of which is secured to the frame 10, and the other end is secured at 74 to the upper end of the lever 68, and an intermediate portion of this cable passes around an idle sheave 75 rotatably supported by the shaft 76. The mechanism of Fig. 6 just describes serves to move the frame 10 positively in a left-hand direction, as in Figs. 1, 2 and 3, and yielding means such as shown in these three figures may be employed to move the frame 10 in a right-hand direction.

By employing cables and cooperating eccentrics in the manner herein described to operate the frame 10, an extremely simple and satisfactory form of operating means is obtained. The dirt and dust that may lodge on the cables and sheaves will not injure them or interfere with their operation, and dust and dirt is prevented from reaching the anti-friction bearings in the manner above pointed out.

What is claimed is:—

1. In combination with a frame supported for back and forth movement, operating means for imparting back and forth movement to the frame, including a pair of cables each anchored at one end and having its other end secured to the frame, an operating shaft provided with an eccentric portion that extends lengthwise of the shaft a substantial distance, two sheaves rotatably mounted upon said eccentric portion in spaced relation to each other and each positioned to engage an intermediate portion of one of the cables, collars secured to the eccentric portion to hold the sheaves from moving lengthwise thereof, and means for rotating the shaft to actuate the sheaves so that they will alternately pull and slack off their respective cables to actuate the frame.

2. In combination with a frame supported for back and forth movement, operating means for moving the frame back and forth, including a rotating shaft having a relatively long eccentric portion, a pair of sheaves rotatably mounted upon the eccentric portion in spaced relation to each other, collars rigidly secured to the eccentric portion of the shaft at each side of the respective sheaves to hold the sheaves from moving lengthwise of the shaft and each collar having an end that projects into the bore of a sheave to close the bore, and a pair of cables each secured to the frame at one end and anchored at the other end and having

an intermediate portion looped about a sheave to be alternately tensioned and slackened off as the shaft rotates.

3. In combination with a frame supported for back and forth movement, operating means for moving the frame back and forth, including a rotating shaft having a relatively long eccentric portion, a pair of sheaves rotatably mounted upon the eccentric portion in spaced relation to each other, collars mounted upon the eccentric portion at each side of the respective sheaves, means for securing each collar rigidly to the eccentric portion of the shaft to hold the sheaves in place, and a pair of cables one looped about each of the sheaves and having one end anchored and the other end secured to the frame and adapted to be alternately tensioned and slackened off as the shaft rotates.

4. In combination with a frame supported for back and forth movement, operating means for imparting back and forth vibratory movement to the frame, including a pair of cables each anchored at one end and having its other end secured to the frame, an operating shaft provided with an eccentric portion that extends lengthwise of the shaft a substantial distance, two sheaves rotatably mounted upon said eccentric portion in spaced relation to each other and each positioned to engage an intermediate portion of one of the cables, collars mounted upon the eccentric portion to hold the sheaves from moving lengthwise of the shaft, means for securing the collars to the eccentric in different positions of adjustment so that the collars at the opposite sides of a sheave may be moved toward and from each other and may be moved with the sheave lengthwise of the shaft, and means for rotating the shaft to actuate the sheaves so that they will alternately pull and slack off their respective cables to actuate the frame.

5. In combination with a frame supported for back and forth movement, operating means for imparting back and forth vibratory movement to the frame, including a cable anchored at one end and having its other end secured to the frame, an operating shaft provided with an eccentric portion that extends lengthwise of the shaft a substantial distance, a sheave rotatably mounted upon said eccentric portion and positioned to engage an intermediate portion of the cable, collars mounted upon the eccentric portion at the opposite sides of the sheave to hold the same from movement lengthwise of the shaft, means for securing the collars to the eccentric in different positions of adjustment so that the collars may be moved toward and from the sheave and lengthwise of the eccentric with the sheave, and means for rotating the shaft to actuate the sheave so that it will alternately pull and slack off the cable to actuate the frame.

6. In combination with a frame supported for back and forth movement, operating means for moving the frame back and forth to vibrate the same, including a rotating shaft having a relatively long eccentric portion, a sheave rotatably mounted upon the eccentric portion, collars mounted upon the eccentric portion at the opposite sides of the sheave to hold the sheave from moving lengthwise of the shaft and each collar having an end that projects into the bore of the sheave to close the bore and exclude dirt therefrom, and a cable having one end secured to the frame and its other end anchored and having an intermediate portion looped about the sheave to be alternately tensioned and slackened off as the shaft rotates. ¹⁵
- In testimony whereof, I have signed my name to this specification.

ALBERT H. STEBBINS.
